BUCKLE

Nadja Buckley, 14 E. 75th St., New York, N.Y.

Filed May 1, 1958, Ser. No. 50,692

Term of patent 3½ years

(Cl. D17—1)

FIG. 1.

FIG. 2.

FIG. 3.

FIG. 4.

I claim:

The ornamental design for a buckle, substantially as shown.
